UNITED STATES PATENT OFFICE.

J. MORTIMER GOLDSMITH, OF BOSTON, MASSACHUSETTS.

VALVE.

SPECIFICATION forming part of Letters Patent No. 293,240, dated February 12, 1884.

Application filed August 13, 1883. (No model.)

To all whom it may concern:

Be it known that J. J. MORTIMER GOLDSMITH, of Boston, county of Suffolk, State of Massachusetts, have invented an Improvement 5 in Valves, of which the following description, in connection with the accompanying drawings, is a specification, like letters on the drawings representing like parts.

My invention relates to a valve of the class 10 known as a "register" valve, in which the valve proper, provided with openings, has a rotary sliding movement on a seat with corresponding openings, the invention being intended as an improvement on a valve for which 15 Letters Patent No. 261,547 were granted to me July 25, 1882. In register-valves the face of the valve is ground to fit accurately upon the seat with such tightness that it is exceedingly difficult for any matter to get between the wearing-surfaces to lubricate them, so that they are 20 liable in time to become worn, so as to no longer fit accurately.

One of the objects of the present invention is to obviate this difficulty by reducing the area 25 of the contact or wearing surface of the valve or its seat, thereby enabling it to be more easily ground, and also permitting the lubricating material to have access to the wearing-surface.

The invention also consists in various details 30 of construction hereinafter to be described.

Figure 1 is a longitudinal section of a valve embodying this invention; Fig. 2, a horizontal section thereof; Fig. 3, a side elevation of the valve proper and a portion of its stem, and 35 Fig. 4 a face view of the valve proper.

The valve consists of the main case or shell 40 a, having inlet and outlet openings b c, and a partition, d, between them, a portion of the said partition being ground smooth to form a valve-seat, d', having a series of openings or ports, e.

The valve proper f consists, essentially, of a disk having a series of corresponding ports or openings, f'. The face of the said valve that bears on the seat is provided with a series of 45 pockets or recesses, i, of the same size and shape as the ports in the valve-seat, thus reducing the actual contact or wearing-surface of the valve to a band lying around the edge of the said recesses. At the periphery of the valve, 50 adjacent to the ports thereof, its under face is

also recessed, as shown at m, thus enabling the fluid passing through the valve to have access to the portion of its wearing-face underlying the periphery of the valve proper, enabling this portion to be lubricated by the said fluid 55 as the valve is opened and closed. The upper portion of the valve-case a, through which the valve proper, f, is inserted, is provided with a cap or bonnet, n, which, in small-sized valves, is screwed thereto, the said cap having the guide- 60 passage n' for the valve-stem o, operated by the handle o'.

In my former patent referred to the movement of the valve in opening and closing was limited by a stop-projection on the handle en- 65 gaging stops on the valve-stem socket, which is screwed to the case a.

The valve-case a is provided with a stop-groove, p, and after the valve is properly ground to its seat it is provided with a stop pin or projection, r, which, by its engagement with the end of the groove p, arrests the movement of the valve in the proper position to register correctly with the ports of the valve-seat.

The valve-stem o is provided with a shoulder, o", engaging a seat at the inner end of the valve-stem-guide passage n' in the cover n, to operate as a packing for the said stem, and in order to provide a suitable connection between the valve-stem and valve, to enable them to be 70 pressed against their seats in opposite directions, the valve is provided with a tubular central hub, f", having one or more projections, f', entering corresponding notches o' in a tubular hood or sleeve, o', projecting downward 75 from the shoulder o" of the valve-stem. The said hood o' and hub f" receive between them the spring t, by which the valve proper and shoulder o" of the valve-stem are pressed to 80 their respective seats in the absence of fluid pressure in the valve.

I claim—

1. In a register-valve, the combination, with the ported seat, of the valve proper, having corresponding ports, openings, and pockets or 95 recesses in the wearing-face of the valve between the said port-openings, substantially as and for the purpose set forth.

2. The ported valve-seat and valve having corresponding ports, and having its periphery 100

notched adjacent to the said ports, substantially as and for the purpose described.

3. The valve-seat and valve, having a recessed hub combined with the valve-stem, having a shoulder and recessed hood, and a spring inclosed in the said hub and hood, which are engaged with one another, substantially as described.

In testimony whereof I have signed my name to this specification in the presence of two subscribing witnesses.

J. MORTIMER GOLDSMITH.
